UNITED STATES PATENT OFFICE

EUGENE R. SEITER, OF RIDGEFIELD PARK, NEW JERSEY, ASSIGNOR TO T. W. & C. B. SHERIDAN COMPANY, A CORPORATION OF NEW YORK

BOOKMAKING MACHINE

Application filed December 9, 1926. Serial No. 153,599.

This invention is a novel book making machine or apparatus, and relates more especially to the class of apparatus used for the manufacture of magazines or other pamphlets. Considered in its entirety, the present invention comprises three combined and cooperating machines, namely, first a machine for gathering or collating signatures or sheets into the groups which are to constitute the pamphlets, second a machine or mechanism for attaching together the assembled groups of signatures, illustrated by the type of mechanism for applying stitches or wire staples adjacent to the back edges of the groups or pamphlets, and third a machine for applying covers or backings to the gathered and attached signature groups; and the invention involves a certain intercombination of said three machines, or subcombinations of less than all of them, as will be more fully set forth.

In order to establish the position of the present invention in the art it is convenient briefly to refer to certain prior known machines and combinations. A signature gathering machine is illustrated in Bredenberg Patent No. 1,177,600 of April 4, 1916, and a more modern gatherer in Gitzendanner Patent No. 1,380,293 of May 31, 1921. A gatherer delivering to a wire stitching machine is shown in expired patent of Juengst 846,923 of March 12, 1907. A machine for binding signature groups and applying covers is shown in Bredenberg Patent No. 1,073,324 of September 16, 1913, involving an endless clamp train carrying the groups through the successive operations; while Bredenberg Patent No. 1,051,074 of January 21, 1913, Reissue No. 14,485 of June 11, 1918, shows a gathering machine delivery connected up for automatic transfer of the signature groups into the clamps of such a machine, to be bound and covered. An improved clamp train machine for binding and covering the signature groups is shown in Bredenberg Patent No. 1,248,252 of November 27, 1917. Clark Patent No. 1,392,117 of September 27, 1921 shows the gluing operation of such a clamp train machine. The triple combina-

tion of a gathering machine, a wire stitching or stapling machine and a clamp train covering machine is shown in Lariviere Patent No. 1,583,889 of May 11, 1926.

It is an object of the present invention to provide a novel intercombination of the gatherer, stitcher and coverer, or any two of them, in a manner to afford increased rate of output, more especially in the case of manufacturing books involving a relatively small number of signatures or sheets. A further object is to afford an apparatus which may be convertible so as to give the usual steps and output for full size or thickness of pamphlets in one adjustment, and in another adjustment the special operation and increased output already explained. A further object is to afford a stitcher capable of such increased output by a multiplex operation, as will be described, and having such convertibility, and which is improved in action and efficiency, especially in regard to the compression of the signature groups for the stitching operation. A further object is to improve the operation and convenience of the gatherer. Other and further objects and advantages of the present invention will be explained in the hereinafter following description of an illustrative embodiment thereof, or will be understood to those skilled in the industry. To the attainment of such objects and advantages the present invention consists in the novel book making machine and the novel features of combination, arrangement, operation and structure herein illustrated or described.

In the accompanying drawings Fig. 1, in top plan view, is a diagrammatic layout of an intercombination of gatherer, stitcher and coverer constituting an illustrative embodiment of the principles of this invention.

Fig. 2, on an enlarged scale, is a plan view of certain details shown in Fig. 1.

Fig. 3 is a right end elevation of the gathering machine partly in section taken substantially on the line 3—3 of Fig. 1.

Fig. 4 is a detail plan view taken partly in section on the line 4—4 of Fig. 3.

Fig. 5 is a top plan view on an enlarged scale of the stitching machine shown in Fig. 1.

The entire combination includes, besides the gathering, stitching and covering units, a conveyor or advancing means by which the successive signature groups are carried along and transferred from each unit to the next, and power drive mechanism with connections extending to the conveyor, the gatherer, the stitcher and the coverer for operating them in coordination.

It will be convenient first to refer to the conveyor or book advancing means, and this is shown as consisting of an elongated flexible traveling element in the form of an endless chain 10, which may be a sprocket chain, and passing around sprocket wheels at its ends, and suitably supported by sprocket wheels or otherwise at various intermediate points, as is well understood in the art. As a means of engaging and advancing the successive signature groups the conveyor chain 10 is shown formed with engaging members or pins 11 which may stand upwardly from the chain at the gatherer, and horizontally at the stitcher, the chain's flexibility permitting this; while the return stretch may be put under tension by idlers, and may travel with the pins above, as indicated in Fig. 3. The engagement of the conveyor with the successive groups may be in various ways, but is illustrated as consisting merely in the thrusting forwardly of the groups by the upstanding pins 11, while the groups are suitably supported flatwise or upright as will be described. The spaces or sections between the engagers or pins corresponds with the spacing of the signature stacks in the gatherer.

Referring to the diagram Fig. 1 the conveyor chain 10 is indicated as passing longitudinally through the length of the gathering unit 12 and thence along the delivery support 13 of the gatherer, which support may be twisted so as to tilt each advancing group from flatwise to upright position, and then along an upright guide chute 14, through which the groups are advanced with the back edges of the signatures downward and so brought into the stitching unit 15, where wire staples or other signature uniting means is applied. The conveyor chain might here be diverted, while the clamping means of the stitcher holds and advances the groups, and a conveyor arranged between the stitcher and coverer, but, diagrammatically the chain 10 is indicated as passing continuously through the stitcher to the covering unit 16, where it passes around a sprocket wheel 17 and returns idly to the initial end of the gathering unit.

The power may be derived from any suitable source, herein represented as an electric motor 18, the shaft 19 of which carries a belt pulley 20. The motor may be of the variable speed type with a dynamic brake control or other device 21 for regulating the speed of the motor so that the drive may be effected

either at the regular or low speed, not above the safe speed for this type of apparatus, or at the special high, double or multiple speed as will be further explained. A belt 22 is shown connecting the motor pulley with a pulley 23 on an initial drive shaft 24, through which power is delivered to all portions of the apparatus. For convenience or incidentally the initial shaft 24 constitutes also the main shaft of the covering unit, although it is obvious that the power connections to the other units need not be carried through the coverer, so long as they all operate in unison. On the drive shaft 24 is shown a bevel gear 25 engaging a bevel gear 26 to which is connected a sprocket wheel 27 connected by a chain 28 with a sprocket wheel 29 on a short transverse shaft 30, which also carries the sprocket wheel or pulley 17 which engages and drives the conveyor chain 10. By these means the power is communicated to the conveyor chain, which will run at the regular or low speed, or at the special or high speed, according to the adjustment of the speed changing device 21.

The shaft 24 is shown extended leftward at 31 beyond the covering unit to an exterior point where connections may be made for the driving of the stitching and gathering units, and this shaft extension being an advantageous point at which to apply the motor or other power source. The shaft 31 is provided with a sprocket wheel 32, which may be termed the regular driving sprocket wheel and a sprocket wheel 32^a which may be termed the special driving sprocket wheel, as these two sprocket wheels, respectively, take part in the regular operation or in the special or multiple operation to be described. The sprocket wheel 32 operates through a sprocket chain 33 to drive a regular driven sprocket wheel 34 carrying a regular clutch member 35 and running loose on a shaft 36, while the sprocket wheel 32^a drives a sprocket chain 33^a engaging a special driven sprocket wheel 34^a carrying a special clutch member 35^a and also running loose on the shaft 36. The special driven sprocket wheel 34^a is shown a multiple of the diameter of the regular driven sprocket wheel 34, namely twice the diameter, so that when the drive is through the special parts the shaft 36 will be driven at relatively half of its speed when driven through the regular connections. The conversion or adjustment from one set of connections to the other may be effected, for example, by a shifting double clutch member 37 slidably longitudinally on the shaft 36 but connected thereto by a key or feather 38 compelling the shaft to rotate with the clutch member. The clutch member has clutch teeth at both ends facing the complementary clutch members 35 and 35^a, and centrally is formed with a groove 39 engaged by the opposite studs of a yoked shipper lever

40, so that by throwing the lever to right or left the connections can be thrown into their regular or their special adjustment.

The shaft 36 is shown as passing through 5 the stitching unit 15 and may be termed the drive shaft of the stitcher, operating the mechanism for forming, driving and clinching the wire stitches or staples. For convenience the gathering unit may be driven 10 by extensions from the same shaft 36, or in such other manner as to partake of the same rate of operation as that of the stitching unit, for reasons to be described. For this purpose the shaft 36 is shown extended at 42, and a 15 pair of meshing gears 43 transmits the rotation to a further shaft 44 extending to the gatherer. As shown in Figs. 1 and 3 the shaft 44 carries at its left end a pinion 45 engaging a gear 46 which carries a pinion 47 20 engaged with a gear 48 mounted on what may be termed the drive shaft 49 of the gathering machine.

Power connections have thus been described for driving the conveyor and the 25 gathering, stitching and covering units in coordination. The regular clutch 35 is shown disengaged from the clutch on the shaft 36, while the special clutch 35^a is engaged thereto, so that, owing to the larger size of the 30 sprocket wheel 34^a the shaft 36 is being driven relatively at half speed, and communicating this drive to the stitcher and the gatherer. The actual speed however is the full or regular speed since it is the plan of this invention, when the special connections are in effect, to operate the source of power 18, or its 35 connections to the initial drive shaft 24, at double speed, the device 21 being shown in such adjustment. The result is that with the 40 adjustment shown the gathering and stitching units are driven at regular or normal speed, or at a safe speed not above the regular speed, while the initial drive shaft 24 is rotating at a multiple or double the regular 45 speed, with the result that the covering unit is driven at double speed and the conveyor chain is driven at double speed. By throwing the lever 40 in the other direction so as to shift the clutch 37, and at the same time throwing the regulator 21 to reduce the drive 50 to regular speed, the entire apparatus, conveyor, gatherer, stitcher and coverer will be operated at regular speed. This will be the usual operation of the machine when manufacturing pamphlets of substantial thickness 55 or containing a large number of signatures or sheets. When the special adjustment is put into effect the gathering unit and the stitching unit will be operated differently, as will be described, this permitting substantially a multiple or double output of the entire combination when operating upon pamphlets of small thickness or having a small number of signatures. The gatherer and stitcher will 60 then continue to be operated at a regular or

safe speed, but in a duplex or multiple manner, as will be described, the conveyor carrying the signature groups through at double or multiple speed, and the covering machine being of a type which can handle the output 70 at the double or multiple speed, thus effectively multiplying the output of the apparatus, and without any resulting drawbacks, when operating on thinner pamphlets.

In one sense the stitcher and gatherer may 75 be considered in one mechanical circuit and the coverer and conveyor in another mechanical circuit, the two circuits relatively adjustable so that in all operations the stitcher and gatherer can be operated at a regular or safe speed, while the coverer and conveyor can be operated either at the same speed, for regular output, or at double or multiple speed, for double or multiple output. While 80 the conveyor has been herein illustrated as 85 a continuous unitary element extending through the gatherer and to and through the stitcher and to the infeed of the coverer, this is not necessary as the conveyor might consist of a series or succession of conveying 90 means operating in tandem. The actuation of the conveyor is herein shown as continuous, thus producing continuous travel of the signature groups, conducing to higher output than the step by step type of travel. In 95 either the regular or special adjustment of the power connections the travel of the groups must be coordinated with the gatherer, stitcher and coverer, so that when disengaging and reengaging the clutch 37 care 100 should be taken that the various units are in coordination. This could be insured by employing a single tooth engagement between clutch member 37 and the respective coacting regular and special clutch members 105 35 and 35^a, the same result being attainable by designating marks on the respective members.

While the present invention could be employed with triple, quadruple or other multiple operation and speed, it is herein for convenience shown employed only for double or duplex operation and speed, and the apparatus will be described as such, it being understood that the same principles could be extended as stated. As usual a series or piles of signatures is maintained in the gatherer, but instead of these being the successive signatures of the book they are arranged in duplex or repeated order. The signatures 110 being lettered "S", the first two piles will be duplicates, and would be designated S^a, S^a, but that the drawing does not extend back to the first end of the gatherer. The diagram Fig. 1 however shows signature pile Sⁱ and piles S^m, S^m, and piles Sⁿ, Sⁿ, considered the 115 end of the series. It being understood that the conveyor travels at double the regular speed, in relation to the operation of the gatherer it is obvious that each accumulating 120 125 130

group will receive a signature only from every other pile, S^a , S^b etc. to S^m and S^n , thus making a complete signature group G, delivered from the final or right hand end of the gatherer. This succession of continuously advancing groups is carried through the stitching point, where the groups are united, and thence to the coverer, where the covers are applied, the final product being delivered as books B as indicated.

The gatherer in its general principles is on the plan of gatherers long well known such as that of the Gitzendanner patent. The drive or main shaft 49 is supported in a heavy elongated frame 51 having upward extensions 52 for the fulcrums of the extractors, etc. Without going into unnecessary detail the signature piles S are contained in a series of boxes 53, with their lower inner sides exposed downwardly. For each signature pile and box there is provided a separator 54, for example of the suction type, operated from the main shaft 49, to contact the lowermost sheet and draw its edge downwardly by suction, and a separator bar or lifter 55 which thereupon thrusts into the box above the lowest signature so as to raise therefrom the weight of the pile, and an oscillating extractor 56 fulcrumed upon an upper shaft or axle 57 so as to swing inwardly and grasp the separated lowest signature and draw it outwardly and release it in front of one of the engagers or fingers 11 of the conveyor, as is usual in gathering machines.

The extractors 56, which are indicated diagrammatically in Fig. 1, may all be operated in unison, moving inwardly in each cycle to grasp the signatures, and moving outwardly together to release the signatures upon the conveyor. The oscillation of each extractor may be through an upper extension 58 connected by link or rod 59 to a suitable cam or crank on a countershaft 60, driven from main shaft 49, all of which connections are well known and require no detail description. Another known feature herein shown is an adjustable receiving support or "basket" 61 comprising a transverse bar carrying a pair of adjustable longitudinal rods or wires, arranged so that as the gripper of an extractor releases a signature it will fall on support 61, and will be removed from the support by the upstanding pin or finger 11 of the conveyor. The accumulating groups rest on a receiving plate or chute 62 as they are pushed forwardly, and this is inclined to ensure the self alinement of the signatures, and the plate is shown adjustable in incline by devices 63 comprising a shaft rotatable at will to alter the adjustment.

The signature gripper comprises the relatively fixed upper jaw 64 and the movable lower jaw 65 having a tail 66 actuated by a rod 67 normally pulled upwardly by a light

spring 68 to hold the jaw open but thrust downwardly to close the gripper on the signature by a cam device 69 on a countershaft 70. These power connections for closing the gripper are actuated by a sprocket chain 71 between the drive shaft 49 and countershaft 70. The downward thrust of cam 69 operates through a strong spring 72, so that the gripper will close firmly but yieldingly on the signature.

It is customary to employ a detecting means or feeler controlled by the thickness of the signature drawn out from the pile, so that in case two signatures are extracted, or none, or a signature of defective thickness, the defect will be indicated and thus permit its correction. For this purpose a bracket 73 is shown supported on the gripper operating rod 67. This small bracket has a hole 74 and therein carries a feeler pin 75 extending downwardly and vertically adjustable to cooperate with a feeler arm or micrometer finger 76 below it. On every descent of the rod 67 the gripper will close upon the signature and the feeler pin 75 will contact and depress the arm 76 so as to throw to the right the upwardly extending micrometer arm 77. The multiplied movement at the upper end of the arm 77 is utilized to detect errors in the signatures extracted. This movement is transmitted to a bell crank lever 78 which carries an engaging member or knife, cooperating with a pair of engaging members spaced to form a gate to receive the knife and carried on a lever 79, on the principles disclosed in the Gitzendanner patent. When the signature is correct the knife lifts to the exact point to pass through the gate, so that lever 79 is not moved, but if too thick or thin the knife strikes and swings the lever 79 as the extractor swings outward. The tail 80 of lever 79 engages a slotted arm 81 attached to an alarm signal 82, shown in its normal position, but adapted to be thrown vertical to signal a defect. This could be accompanied by an audible alarm; and it is also well known to connect the detecting mechanism to stop the machine or effect the discarding of the defective signature or group. A control rod or hand bar 83 is shown by which the machine can be stopped or started at will.

While such feeling and detecting devices have been generally used and known they are subject to a disadvantage in that when made and arranged in an effective and rugged manner for ordinary detection, namely of signatures consisting of a number of thicknesses of paper, they are not sufficiently sensitive and can not be adjusted for uniform action in detecting errors in very thin signatures, or single sheets. For example if the gripper should pull out two instead of one single sheet it would be important to detect this and yet the ordinary detector would not be reliable. I have therefore provided the

adjustment shown in Fig. 3 and enlarged in Fig. 4. This consists in providing means of adjusting the feeler pin 75 along the bracket 73, for example by a series of holes or a slot in the bracket. Thus, besides the hole 74, is shown a second hole 74^a, so that the feeler 75 can be shifted to position 75^a, thus bringing the feeler pin nearer to the fulcrum of the micrometer arm 76. As shown in full lines the arrangement is satisfactory for detecting usual signatures, but when shifted to the dotted line position it is obvious that any variation of the thickness of the gripped signature will cause a much greater multiplication of movement at the top of the upward arm 77, thus indicating a very fine error of thickness. The sensitivity of the feeling device depends on the distance of the feeler pin from the fulcrum of the feeler arm. In Fig. 3 the dotted position of the pin is about one third as far from the fulcrum as is the full line position, giving therefore three times the sensitiveness, and this principle can be carried to any desired extent.

The following are the alterations in the gatherer when changing from regular to multiple operation and vice versa. For duplex operation the signatures are arranged in duplex order as indicated in Fig. 1, where as they will be in single series order for regular operations. The extractors may operate in the same manner in either case and at the same or regular speed. Indeed it is highly important that the gathering machine, with the fairly heavy oscillating extractors, should not be operated above a safe speed. The extractors possess inertia and these and the connected parts would be the cause of prohibitive vibration, wear and defective action. The mechanism therefore of the gatherer will be substantially unaltered, except that the conveyor 10 which runs through the length of the machine and on which the accumulating signature groups are carried, will be operated at a relative double speed. This coordinates with the duplex arrangement of the signatures since each conveyor space or unit will, in the duplex operation, travel the distance of two signature boxes, and thus receive only one signature of each variety S^a to S^a. By this arrangement and operation the gatherer, when used for pamphlets of half size or smaller, can be made to turn out double or multiple the number of pamphlets in a given time, without increasing the actual speed of the extractors and other signature handling parts. The successive signature groups are identical, the same as with regular operation, and this traveling series of signature groups G passes out from the gatherer delivery and is tilted to upright position and thence fed into the wire stitching machine 15.

The wire stitching machine is representative of any suitable mechanism for attaching together the signature groups. Preferably it

forms, drives and clinches wire stitches or staples. This machine, like the gatherer, comprises heavy reciprocating parts, and its safe and proper speed of operation is thereby restricted. It is the plan of the present invention to operate the stitcher at the same regular speed for multiple as well as for regular operation, and cause it to handle the increased number of books by substantially duplicating the staple forming, driving and clinching mechanisms, so that the stitcher in each actuation receives two books and staples them simultaneously and delivers them for conveyance to the covering machine. A similar result obviously could be obtained by employing two separate or distinct stitching machines, one following the other, the first one attending to the stitching of every second book, and the second one attending to the stitching of the remaining books. In either case, however, an alteration or adjustment is here made in the stitching mechanism in order that it may cooperate properly with the conveyor, traveling at slow speed in the regular operation and traveling at double or multiple speed in the special operation of the apparatus. This, as will be described more in detail, is herein accomplished by causing the stapling devices to move forwardly along the path of book traveling during the driving and clinching of the staples at a slow or regular speed during the regular operation, but at an increased or double speed with the duplex operation, and preferably at the same time altering the amplitude of such reciprocation so that the staple driving and clinching actions will be allowed the full period of time in either case.

The wire stitcher is shown only diagrammatically in Fig. 1, but more in detail in the plan view of Fig. 5. The general principles are well known and the mechanism will not be described any more in detail than necessary to disclose the principles of the present improvement. The wire stitcher frame 85 extends longitudinally of the direction of travel and supports the various operating mechanisms, all of which are actuated from the stapler main shaft 36 already referred to.

Certain parts of the stapler, including what may be termed the carriage or table 86, are arranged to be reciprocated longitudinally as stated. Outside of the stitcher table is shown a driving bar 87, which does not partake of the longitudinal reciprocation, but is capable of being thrust inwardly by toggles 88 operated by a cam 89 on a countershaft 90 to produce the driving movements of the stapler. At the other side of the book path is a pressure bar 91 operated by toggle mechanism 92 and connection 93 to move inwardly at the proper point of time to engage and squeeze each book against the opposite table. As already stated these group clamping or

squeezing parts 86 and 91 are arranged to reciprocate bodily, and in fact, as will be explained, they will preferably be moving forward faster than the travel of the conveyor 5 chain 10 at the time of gripping the books, so as to carry the books forwardly away from the engaging pins 11 of the conveyor, thus independently holding the books during the staple driving and clinching operations and 10 subsequently releasing the books to be again engaged by the conveyor, while the stapling devices return for a repeated operation. It will be noted that the parts 86 and 91 are double the length necessary to operate upon 15 a single book and so are able to receive and staple two books in one operation. Thus the table 86 is shown as carrying two staple forming devices or stitcher heads 94 which may be termed the regular stapling heads, and 20 two additional or special stapling heads 94^a; these so arranged that while the heads 94 are forming two staples to be driven in one book the devices 94^a are operating similarly in respect to the preceding book, so that, as 25 stated, the stitching mechanism at each operation staples two successive signature groups, giving double rate output without increasing the speed of the mechanism. The wire for the staples may be furnished by two 30 spools 95 supplying wire to the two staple forming devices 94, and two other spools 95^a furnishing wire to the staple formers 94^a; through wire straighteners 96.

The two pairs of stitcher heads 94 and 94^a 35 may be of well known type, with wire cutting and staple forming means operated by the staple driver, and wire feeding means operated during the return movement of the table by underneath mechanism 97 shown in dotted 40 lines, this being adjustable to conform to the throw of the table, whether long or short, which is utilized for the feeding operation. Each stitcher head has a clincher extension 98 beneath the book path, and the clinching 45 devices may be actuated by a slide rod 99 movable in the presser 91, and a contact 100 for throwing the rod to effect the clinching, with a complementary contact 100^a for restoring the parts on the return motion. The 50 table is shown midway in its forward motion, with the clamping elements 86, 91 closed on the two books (not shown), and the staples about to be driven, and later clinched, after which the pressure bar 91 will withdraw outwardly so as to afford a wide opening to receive from the guide chute 14 the next two 55 signature groups. Each of the two sets of stitching devices might consist of three instead of a pair of devices.

60 It remains to describe the longitudinal reciprocation of the wire stitching mechanism, or rather of the stitcher table 86, pressure bar 91, and parts carried thereby. There is shown a vertical shaft 101, driven by bevel 65 gear from the main shaft 36, and making one

complete turn for each cycle. At its upper end the shaft 101 drives a crank arm 102 carrying a block 103 connected by a rod or link 104 with the under side of the table. This gives a smooth cross head motion to the reciprocating parts, and the motion is timed, so that the book is gripped during the forward acceleration of the table at a time when the mechanism is traveling slightly faster than the conveyor, so that the books are 70 clamped, held and carried forward without interference with the conveyor, the book being again released after the staple driving and clinching actions and before the conveyor pins have again overtaken the books. The 75 crank 102 and block 103 have not only the adjustment which is shown in full lines, giving double amplitude or throw of reciprocation, but also an adjustment of the block 103 to the position 103^a wherein the amplitude is half of that shown, this or other adjustment being effected by a screw 105. The shorter crank arm, with the shorter throw is such as to take part in the regular operation 80 of the apparatus, with the conveyor traveling at regular or slow speed.

With the full or double arm adjustment, and the double reciprocation throw indicated by the path 106 of the crank pin, the machine is adapted to the double speed travel of the conveyor, and as the double speed is accompanied by double amplitude of throw manifestly the period of action is the same in the 85 two cases, so that the full period of time is allowed for the staple forming, driving and clinching actions. With this special or double throw it will readily be seen that the stitching table with the two pairs of forming heads, after applying staples to two signature groups, move back to initial position while the conveyor moves forward, so that 90 on the next actuation the next two succeeding groups are operated on. The stitching machine is thereby rendered capable of double the normal output, without any increase 95 or change of speed or action with the exception of the enlarged crank throw producing the double lengthwise reciprocation, and the resetting of the wire feeding cam mechanism 100 97, as stated.

When operating in the regular manner, at 105 regular amplitude of reciprocation, upon a series of groups traveling at regular speed, each book after being stapled by the first pair of heads 94 would be subject to being again stapled by the second pair 94^a, thus inserting four staples in each book. Although the two additional staples could be offset with respect to the first two this operation is undesirable, and the preferred operation is to render inoperative the stapling devices 94^a during regular or slow operation of the apparatus, either by disconnecting the staple forming devices or preventing the feed of the wires thereto; or, the middle two staple 110 115 120 125 130

formers could be thrown out of action, so that each traveling group would receive one staple in one operation and its second staple in a subsequent operation; or the forming heads could be re-positioned longitudinally to give the desired result.

From the stitcher the continuous succession of stapled signature groups travels to the cover 16, which is preferably driven in the same manner as the conveyor, namely in a continuous manner and at the regular low speed or the special high or double speed, the same as the conveyor. The coverer is shown as comprising a frame or track 109 around which travels an endless train of clamps 110. The mode of construction and connection of the clamps may be substantially as shown in said Bredenberg Patent 1,248,252 and need not be described here. The clamps may be driven from a large horizontal sprocket 111 through a reducing bevel gear 112 on the shaft 24, in such ratio that the clamp train will advance the distance of one clamp for each signature group. The signature groups pass along with the conveyor 10 and are brought up into the clamps 110 by an infeed 114, the mechanism of which may be similar to said Patent 1,248,252, and following the infeed, around the horizontal orbit of the clamps, are indicated a gluer 115, a cover applier 116 and a cover breaker 117, the mechanisms of which may be similar to said prior patent. From the cover breaker the completed pamphlets travel around one end of the machine and are discharged by the opening of the clamps, being received upon a delivery support or belt 118. The covering machine of said Bredenberg patent is capable of the relatively double speed referred to so that, as already explained, the coverer and the conveyor may be run at the double speed when desired, while the gatherer and stitcher are operated at the regular or low speed. The clutch 37 may be considered as a means of allowing the coverer and conveyor to be run at double speed without increasing the speeds of the gatherer and stitcher. In one sense the clamp train 110 of the conveyor constitutes a conveying means which is a continuation of the conveyor chain 10, and the two together may be considered as a conveying means extending through the gatherer and stitcher and through the coverer from the infeed to the delivery, while the signature groups are gathered and subsequently stitched and thereafter glued, covered and shaped by the cover breaker before final delivery as completed products.

In fact, the uniting or stapling of the groups could be effected in the same clamps or clamp train in which the covers are applied, so long as, in the case of stapling, the amplitude of travel and period of action are increased with the duplex operation. Where a stitching machine is used, as herein

described, whether or not fed with groups direct from a duplex operating gatherer, its stapled product may be conveyed to the covering unit, or in some cases may be merely discharged into a packer box, partially obtaining the advantages hereof. For the purposes of the duplex operating stitcher the double rate supply of signature groups may be provided otherwise than as shown, for example by a gatherer using alternating sets of extractors with staggered boxes of signatures, as covered in Bredenberg Patent 1,177,600.

With the full combination, as disclosed, the regular operation may involve a speed as high as 60 to 70 per minute for the operation of the gatherer, stitcher, coverer and conveyor, whereas with the duplex or "two-up" operation the conveyor and coverer will run at 120 to 140 per minute, the gatherer at 60 to 70 per minute, with duplex signature arrangement, and the stitcher at 60 to 70 per minute, with two groups stapled in each action, and the reciprocation amplitude doubled to allow full time for the stapling operations.

The general combination may be briefly summarized in the following terms adaptable for expressing the points of novelty in the form of claims. The several mechanisms or units may be described as follows. The gathering mechanism is one in which the signature supplies or piles may be arranged in a given multiplex order, meaning that the signatures are in repeat order, duplex, triplex, etc. This a matter rather of arrangement than of mechanism and the arrangement, usually duplex, is to correspond with the rate of advancing travel of the signature groups gathered from the successive supplies. The gatherer may be described as one having a series of signature extractors which operate upon all the signature supplies in each cycle period. By the cycle period is meant the period of time required by each swinging extractor to go through its complete cycle of movements, and this recurring period or interval may be considered as the operative or basic period of the entire book making apparatus, since substantially the limit of safe speed of the gatherer controls the operation of the entire apparatus. The cycle period may vary; for example, if the gatherer is adjusted for sixty operations per minute the cycle period will be 1/60th minute or one second, while if it is run at seventy cycles per minute the period will be 1/70th minute. The convertibility of the apparatus for either the special multiplex operation, or the regular or usual operation, wherein the signature supplies are arranged seriatim or in single order, is not an essential, but a subordinate feature of the present invention; and manifestly, on the principles of the invention, the apparatus could be converted from the du-

plex or multiplex operation to the regular or single operation, and vice versa, or on the other hand could be converted from one multiplex operation to another, for example from 5 duplex to triplex operation, and vice versa, depending on changes in the thickness of the pamphlets to be manufactured, or the number of signatures contained therein.

Interconnecting the gatherer and stitcher 10 or equivalent book uniting means is the conveying means, which may consist of one or more group advancing devices arranged in tandem. The conveying means hereof operates to advance the accumulating signature 15 groups through the gatherer at the travel rate of a given plural number of book spaces or sections in each cycle period; that is, the speed or rate of advance of the groups is two or three or more book spaces or sections of 20 the conveyor in each cycle period or extracting operation. As the multiplex arrangement of the signature supplies corresponds with this multiplied travel rate it follows that each group will receive one signature of each 25 kind, so that each group will be complete, whereas two or three completed groups will issue from the gatherer in each cycle period. Thus if the cycle period is one second and the arrangement is duplex two complete 30 groups will issue every second. The conveying means operates to continue the travel of the successive groups to the stitching point.

The next unit, or that which unites the successive groups, is shown as a stitching mechanism of certain characteristics. The usual stitching mechanism has only a single stitching set, comprising for example two staple drivers working on the same book at the same 35 time, but the present invention is distinguished from the use of such a stitcher in that it embodies a plurality of stitching sets operating to unite the plural number of successive groups in each cycle period, that is to say two 40 or three or other plural number of groups, as the case may be in each basic cycle period, as determined by the operation of the gatherer, as already described. The distinction mentioned is a highly important one, especially 45 with a continuous travel apparatus, since the use of a plural number of stitching sets, namely two sets, as shown, enables two groups to be stapled in the same operation and cycle period, and preferably simultaneously, thus 50 enabling the duplicate number of signature groups per minute to be united without cutting in half the already brief period of time available for effecting the staple forming, driving and clinching operations. Specifically, with the herein described stitcher, the 55 full stitching time is permitted by employing the two complete sets of stitching devices and reciprocating them longitudinally of the travel at the increased or double speed of the 60 conveyor, but at increased or double ampli-

tude, so that the stitching devices may have the usual or full time desirable for the satisfactory performance of their operations. The plurality of stitching sets referred to may comprise stitching devices arranged differently from those shown; for example one group might receive one staple in a first position and a second staple two positions beyond, while a second book receives its first and second staples in alternating positions, so 70 that as said books are receiving their second staples a third book and a fourth book may be receiving their first staples. As with the described arrangement there are a plurality of stitching sets, and each stitching device 75 may be allowed its full time for operation.

A feature of claim in the described stitcher is what may be termed the counterbalanced smashing action in the compression of the group between the pressure bar 91 and stitching table 86. The groups, and the folds or bends at the back of the signatures tend to resist the tight compression which is desirable. The heavy opposite compressing members 86 and 91 and parts carried by them, are thrown 80 forcibly together upon the book, being timed to meet upon the book and thus give an effective smashing compression, which is counterbalanced in the sense that the operating momenta or inertias of the two members are 85 opposed, not merely giving ideal compression, but mutually taking the impact of each other and so minimizing general vibration or 90 shock in the machine. The compression is momentarily held, during the stitch driving 95 and clinching, by dwells in the mechanisms operating the two members. The compressing action moreover is a rotary one in the sense that the actuating cams, e. g. 89, which throw the members inward are heavy and 100 continuously rotating, so that a fly wheel or 105 inertia effect is produced, assisting in the permanent creasing and flattening of the signature group and the back folds thereof, to the improvement of the product of the apparatus. 110

The covering mechanism, receiving the stitched groups from the stitcher, may be described as having a clamp train or other traveling conveyor which carries the groups in procession to the cover applying devices, 115 namely at the rate of a plural number of books in each cycle period, that is, the same plural number as is defined by the travel rate of signature groups through the gathering machine. As stated the speed of the traveling 120 conveyor or clamp train of the covering mechanism corresponds to that of the conveying means which carries the groups through the gatherer and to the stitcher, and readjustments of speed of conveyor and covering 125 mechanism may be effected without requiring the gatherer or stitcher to be operated at excessive speed.

Thus there has been described a book making apparatus embodying the principles and 130

attaining the objects of the present invention. Since many matters of combination, arrangement, operation and structure may be variously modified without departing from the principles, it is not intended to limit the invention to such matters except to the extent set forth in the appended claims.

What is claimed is:

1. A book making apparatus comprising conveying means having connections for actuating it for advancing a succession of signature groups at the travel rate of a given plural number of book spaces or sections in each cycle period, and uniting mechanism having a plurality of uniting sets and means for operating them to unite such plural number of successive groups in each cycle period.

2. A convertible book making apparatus as in claim 1 and wherein is means for reciprocating the uniting sets along the travel line, means associated with the actuating connections for adjusting them to alter the speed of the conveying means, and means associated with the reciprocating means for adjusting them to alter the amplitude of reciprocation of such uniting sets without altering the rate of action of said uniting sets.

3. A book making apparatus comprising conveying means having connections for actuating it for advancing a succession of signature groups at the travel rate of a given plural number of book spaces or sections in each cycle period, and uniting or stitching mechanism having a plurality of uniting sets and means for operating them to unite such plural number of successive groups in each cycle period.

4. A book stitching or uniting mechanism having a plurality of uniting devices in longitudinal alinement, a guide for a longitudinal procession of books, means for feeding a plurality of separate books in tandem to the respective uniting devices in each operation, and means for operating the uniting mechanism to unite such plurality of books in tandem in each operation.

5. A book stitching or uniting mechanism having a plurality of sets of uniting devices in longitudinal alinement, a guide for a procession of books, means for feeding a plurality of successive books to the uniting mechanism in each operation, means for operating the uniting mechanism to unite such plurality of books in each operation, means for reciprocating the devices along the line of book travel, and means for adjusting the amplitude and speed of throw of such reciprocation.

6. A book stitching or uniting mechanism having a plurality of sets of wire stitching devices in longitudinal alinement, a guide for a procession of books, means for feeding a plurality of successive books to the uniting mechanism in each operation, means for operating the uniting mechanism to unite such

plurality of books in each operation, said wire stitching devices having means for reciprocating them along the line of book travel, means therein for adjusting the amplitude and speed of throw of such reciprocation, and means for adjusting the wire feeding action of the wire stitching devices accordingly.

7. A convertible book making apparatus comprising conveying means having connections for actuating it for advancing a succession of signature groups at the travel rate of a given plural number of book spaces or sections in each cycle period, stitching mechanism having a plurality of stitching sets and means for operating them to stitch such plural number of successive groups in each cycle period, and having means for reciprocating the stitching sets along the travel line either at low or high speed and with correspondingly short or long amplitude, and one or more sets being adapted to be thrown out of action when the stitching is to be operated at low speed and short amplitude.

8. In a pamphlet making machine for uniting signature groups by stitching the combination of a pair of opposed movable compression members both of substantial weight and momentum, means for moving said members forcibly simultaneously towards each other upon the opposite sides of the signature group to give a balanced smashing action thereon, and means for stitching the signature group when so compressed.

9. In a stitching machine for uniting signature groups the combination of a pair of opposed compression members both of substantial weight and momentum, means for moving said members simultaneously towards each other upon the signature group to give a balanced smashing action thereon and for holding such members after the smashing compression to retain the group under forcible compression during the stitching operation, and means for stitching the group while so held compressed.

10. In a stitching machine for uniting signature groups the combination of a pair of opposed compression members both of substantial weight, means for moving said members simultaneously towards each other upon the signature group to give a balanced smashing action, comprising heavy rotary actuators or cams, giving a fly wheel effect assisting in flattening the group, and means for stitching the group when so compressed.

11. In a book making apparatus of the kind having gathering means, followed by uniting means, for the signature groups, and with means for conveying the groups in procession, from one to the other; the combination of such conveying means, the same having adjustable connections for actuating it to advance the succession of signature groups at the travel rate of a single group in each

cycle period of the apparatus or a multiple thereof, according to adjustment, to bring them successively to the uniting point, while maintaining them in grouped condition, and 5 uniting mechanism having a plurality of uniting sets, and adjustable means for operating such sets to unite, according to adjustment, either a single one or a multiple number of signature groups in each cycle period, 10 corresponding with the travel rate of the conveyor.

12. In a book making apparatus of the kind having gathering means followed by uniting means for the signature groups, and 15 with means for conveying the groups in procession, from one to the other; the combination of such conveying means, the same having connections for actuating it to advance the succession of signature groups at the 20 travel rate of a multiple number of groups in each cycle period of the apparatus, to bring them successively to the uniting point, while maintaining them in grouped condition, and uniting mechanism having a plurality 25 of stitching sets, with means for operating them to unite a multiple number of signature groups in each cycle period, and means for reciprocating the stitching sets bodily along the travel line at a speed corresponding 30 with the conveyor speed and in a period corresponding with the cycle period.

In testimony whereof, I have affixed my signature hereto.

EUGENE R. SEITER.

DISCLAIMER

1,791,081.—*Eugene R. Seiter, Ridgefield Park, N. J. BOOKMAKING MACHINE.*
Patent dated February 3, 1931. Disclaimer filed September 9, 1939, by
the assignee, *T. W. & C. B. Sheridan Company.*

Hereby enters this disclaimer to claims 1, 3, 4, and 12 of said patent; without
however intending to disclaim the subject matter of claim 2, expressed subordinately
to said claim 1.

[*Official Gazette October 24, 1939.*]
